(57) **CLAIM**

The ornamental design for a toilet brush holder assembly, as shown and described.

DESCRIPTION

FIG. 1 is a top perspective view of a first component of the toilet brush holder assembly of FIG. 17, shown in a closed state, isolated from the assembly to show aspects of the design not seen when fully assembled, for clarity;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of a second component of the toilet brush holder assembly of FIG. 17, shown isolated from the assembly to show aspects of the design not seen when fully assembled, for clarity;

FIG. 10 is a bottom perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a top perspective view of a toilet brush holder assembly showing my new design fully assembled and in a closed state;

FIG. 18 is a bottom perspective view thereof;

FIG. 19 is a front view thereof;

FIG. 20 is a rear view thereof;

FIG. 21 is a left side view thereof;

FIG. 22 is a right side view thereof;

FIG. 23 is a top view thereof;

FIG. 24 is a bottom view thereof;

(Continued)

FIG. 25 is a top perspective view of the first component of FIG. 1 shown in an open state;

FIG. 26 is a top perspective view of the toilet brush holder assembly of FIG. 17, shown in an open state; and,

FIG. 27 is a top perspective view of the toilet brush holder assembly of FIG. 17 in a state of use with additional environment.

The broken lines in FIG. 27 depict an environmental toilet brush handle that forms no part of the claim, while all other broken lines depict portions of the toilet brush holder assembly that form no part of the claimed design.
